Specification for Design.

Patented Oct. 29, 1918.

Application filed April 22, 1918. Serial No. 230,132. Term of patent 3½ years.

To all whom it may concern:

Be it known that we, LEO GILLIG and CHESTER GILLIG, citizens of the United States, and residents of San Francisco, in the county of San Francisco and State of California, have invented a new, original, and ornamental Design for an Automobile-Top, of which the following is a specification, reference being had to the accompanying drawing, forming part thereof.

In the drawing:—

The figure illustrates a three-quarter side elevation in perspective.

Copies of this patent may be obtained for five cents each, by addressing the "Commissioner of Patents, Washington, D. C."

What we claim is: —

The new and ornamental design for an automobile top, substantially as shown.

In testimony whereof, we have hereunto set our hands this 21st day of February 1918, in the presence of the two subscribed witnesses.
